R. E. L. JANNEY,
DAMPER FOR TALKING MACHINES,
APPLICATION FILED JUNE 25, 1918.

Patented Oct. 18, 1921.

UNITED STATES PATENT OFFICE.

ROBERT E. L. JANNEY, OF CHICAGO, ILLINOIS.

DAMPER FOR TALKING-MACHINES.

1,394,176.

Specification of Letters Patent. Patented Oct. 18, 1921.

Application filed June 25, 1918. Serial No. 241,732.

To all whom it may concern:

Be it known that I, ROBERT E. L. JANNEY, a citizen of the United States, residing at Chicago, county of Cook, State of Illinois, have invented certain new and useful Improvements in Dampers for Talking-Machines, of which the following is a specification.

My invention relates to varying the tone of a talking machine at will while the same is in operation, said variation being accomplished by means capable of being operated at a distance therefrom to suit the convenience of the operator, this operation being similar to the well known action of the pedals of a piano or other musical instrument. It is obvious that this variation must be capable of being attained instantaneously, as sometimes it may be desired to vary the tone even of a single note, and it is obvious also that the adjustment must not interfere with the action of the sound-box or its part in their movements following the undulations in the record.

This object I accomplish in the manner and by the means hereinafter more particularly described and claimed, reference being had to the accompanying drawing, in which:

Figure 1 is a side elevation of a sound-box having my improved damper attachment applied thereto, said box being shown partly broken away.

Fig. 2 is a front view of the same.

Fig. 3 is a top plan view detached of the bracket and its parts which support the damper.

Fig. 4 is a front view of said bracket with parts detached.

Fig. 5 is a detail perspective view of the upper portion of the damper supporting bracket.

Fig. 6 is a detail view of the damping pad.

Similar numerals of reference denote corresponding parts in the several views.

In the said drawing, the reference numeral 1 denotes a conventional sound-box, having fixed therein the usual diaphragm 2, and having pivotally mounted at its bottom a bracket 3, carrying the stylus 4, all of which parts are of conventional form. Clamped to the top of the sound-box, by means of arms 5, engaging the inner face of the sound box, and legs 6 and 7 disposed against the rear face of the sound-box, is a bracket 8. One of the legs 7 is pivoted to

the bracket 8 at 9, and both of said legs 6 and 7 are inturned or hooked at their lower ends at 10 to engage around the edge of the sound-box 1, as shown. In order to clamp 60 said legs in their adjusted position I provide a rod 11 swiveled in a lug 12 on one of the legs and having its other end passed through a similar lug 13 on the other leg, said rod being threaded at its outer end to 65 receive a wing nut 11', whereby the legs 6 and 7 may be drawn toward each other, more firmly to clamp the device upon the back of the sound-box, in a manner readily understood. Pivoted in ears 14 on said bracket 70 is a member 15, apertured near its upper end to receive therein a rod 16, that at its other end passes through an upstanding lug 17 on the bracket 8, the rear end of said arm being screw-threaded to receive thereon a nut 18, 75 and there being disposed on said arm between said nut and the member 15 a coiled spring 19. Said member 15 at its lower end carries a holder or socket 20, in which is movably disposed a damping pad 21, fixed in a thimble 80 22, that in turn is attached to a rod 23 passing through a flexible sheath 24, which at its upper end has fixed thereto a hand-hold 25, beyond which said rod 23 projects, the latter at its upper end being provided with a knob 85 26, and there being disposed between said knob and said hand-hold 25 a coiled spring 27.

In operation, the member 15 will be pressed normally to the position shown in Fig. 1, 90 through the tension of the spring 19, in which position the socket 20 will contact with the sound box frame and the damping pad 21 will be out of engagement with the diaphragm 2, as seen in Fig. 1. When it is 95 desired to dampen the sound of the diaphragm 2, a pressure exerted upon the knob 26, will, through the rod 23, force the pad 21 downward obliquely against the diaphragm 2 near its outer edge. A further 100 downward pressure on the knob 26 will cause said pad to move in sliding contact with the diaphragm 2 toward the point of attachment thereto of the stylus 4, this movement being permitted by reason of the pivotal support of said damper through the member 15, the spring 19 yielding sufficiently to accomplish such movement, and necessarily exerting a gradually increasing tension upon the member 15 as the pad 21 approaches the 105 stylus 4.

It is obvious that a damper touching the

diaphragm will affect the tone in proportion to its distance from the center of vibration, and for that reason I have provided means for shifting the point of contact toward and from said center, thereby obtaining a maximum range of variation, it being understood that the damper or pad 21 is adapted to be moved far enough actually to reach the point of contact between the stylus 4 and the diaphragm 2, in which position the greatest damping effect is obtained.

It has been found essential that the damper 21 shall be formed of some substantially non-resilient material, as the employment of yielding or resilient material, such as felt or rubber, has been found without any substantial damping effect, it being essential that the damper be of substantially unyielding material, and in order to protect the diaphragm from scratching, and yet not affect the firm contact of the damper 21, said damper is thinly covered with felt or other suitable material 27 as shown in Fig. 6, for the purpose of absorbing any scratching or jarring vibration which otherwise would be produced between the damper 21 and the diaphragm particularly at the moment of contact. It has been found that not only does my improved device serve effectively as a damper, but that the contact of the pad 21 with the diaphragm cuts off all excess vibration of the diaphragm and thereby improves the tone of the sound.

I do not wish to confine myself to the specific construction shown for applying the damping pad to the diaphragm, as the details of the same may be varied materially, the essential objects of the invention being to provide means for damping the diaphragm, and also for varying the point of contact of the damper with respect to the stylus or center of the diaphragm, to give the greatest range of variation. Thus, I may employ means other than the rod 23 for manipulating the damper, such, for instance, as a pneumatically operated mechanism, as readily will be understood.

Having thus described my invention, what I claim as new and desire to secure by Letters Patent, is:

1. A damper for talking machines, comprising a damping pad, and means for adjusting it into and out of contact with the talking machine diaphragm, and, while in contact therewith varying its position on said diaphragm.

2. A damper for talking machines, comprising a damping pad formed of substantially unyielding material, and means for

adjusting it into and out of contact with the talking machine diaphragm, and, while in contact therewith, varying its position on said diaphragm.

3. A damper for talking machines, comprising a damping pad, means for pivotally supporting the same in position, means for forcing it into contact with the diaphragm, and means for varying its position on said diaphragm while in said contact.

4. The combination with a sound-box, and its diaphragm, of a bracket clamped to said box, a damper holder pivoted to said bracket, a damper adjustably carried by said holder, and means for forcing said damper into contact with said diaphragm and for shifting it while in contact therewith toward and from the stylus.

5. The combination with a sound-box, and its diaphragm, of a bracket clamped to said box, a damper holder pivoted to said bracket, means on said bracket and damper holder for applying spring pressure to said holder, a damper adjustably carried by said holder, and means for forcing said damper into contact with said diaphragm.

6. The combination with a sound-box, and its diaphragm, of a bracket clamped to said box, a damper holder pivoted to said bracket, means on said bracket and damper for applying spring pressure to said holder, a damper adjustably carried by said holder, and means for forcing said damper into contact with said diaphragm and for shifting it while in contact therewith toward and from the stylus.

7. A device of the character specified comprising a sound box, a diaphragm mounted in the sound box, actuating mechanism connected with substantially the central portion of said diaphragm and capable of vibrating said diaphragm when in co-operation with a suitable record, and a stop of hard material and having a relatively small portion bearing on the face of the diaphragm, and means to guide said stop whereby it may be adjusted across the face of the diaphragm toward or from the central portion of said diaphragm.

8. A device for limiting the amplitude of vibration of a diaphragm of a phonograph reproducer or the like comprising a non-abrasive stop of hard material, movable means for carrying said stop to permit said stop to be moved across the face of said diaphragm, and means for adjusting the pressure of said stop against the diaphragm.

In testimony whereof, I hereunto set my hand this 14th day of June, 1918.

ROBERT E. L. JANNEY.
